UNITED STATES PATENT OFFICE.

JOHN W. MC AULIFFE, OF PELHAM, NEW YORK.

SELF-STROPPING SAFETY-RAZOR.

1,367,158.

Specification of Letters Patent.

Patented Feb. 1, 1921.

Application filed April 16, 1920. Serial No. 374,301.

To all whom it may concern:

Be it known that I, JOHN W. MC AULIFFE, a citizen of the United States, residing at town of Pelham, county of Westchester, 5 State of New York, have invented a certain new and useful Improvement in Self-Stropping Safety-Razors, and declare the following to be a full, clear, and exact description of the same, such as will enable others 10 skilled in the art to which it pertains to make and use the same, reference being had to the accompanying drawings, which form a part of this specification.

My invention has for its object to produce 15 a simple and novel safety razor combining within itself a stropping device and means for supporting a blade in a shaving position or in a stropping position.

The various features of novelty whereby 20 my invention is characterized will herein-after be pointed out with particularity in the claims; but, for a full understanding of my invention and of its object and advantages, reference may be had to the following 25 detailed description taken in connection with the accompanying drawings, wherein:

Figure 1 is an end view of a razor arranged in accordance with the present invention;

Fig. 2 is a transverse section on a plane parallel with the plane of Fig. 1;

Fig. 3 is a section taken approximately on line 3—3 of Fig. 1;

Fig. 4 is an end elevation of a modified 35 form of razor, the handle being broken away;

Fig. 5 is a view of the razor illustrated in Fig. 4, showing the opposite end thereof;

Fig. 6 is a section taken approximately 40 on line 5—5 of Fig. 4, the full line construction showing the razor blade in the stropping position and the dotted lines showing the blade in an intermediate position between the stropping and shaving positions;

Fig. 7 is a section on line 7—7 of Fig. 6; and

Fig. 8 is a longitudinal axial section through the blade-supporting shaft or bar.

Referring to Figs. 1 to 3 of the drawings, 50 1 represents a casing or housing open at the top, the same being conveniently made in the form of a semi-cylindrical trough from the bottom of which depends a central rib-like part, 2, forming a handle. Overlying the member 1 is a housing or casing, 3, open

at the bottom and decreasing gradually in width toward the top. The members 1 and 3 may conveniently be secured together by means of screws, 4, passing through overlapping portions thereof, or they may be fastened together in any suitable way. The housing member, 3, is also open at the top and, extending laterally and outwardly from one long edge at the top thereof is a 55 flange or shelf, 5, shaped in any usual or suitable way to support and guard a single edged razor blade. The housing member, 3, is open on the side opposite that on which the blade support, 5, is located, that is, on the rear side. The open rear side of the upper member of the housing is closed by a wall or door, 6, hinged at its lower end, as indicated at 7, to the member 3 and having at the upper end thereof a hood, 8, in the 60 form of an inverted trough which, when the door is closed as shown in the drawings, overlies the open upper end of the housing. The housing member, 3, is preferably provided with inwardly-directed flanges or 65 ledges, 9, along the rear edges of its side walls for the purpose of providing stops or bearing strips against which the door may rest when closed. Means are preferably provided tending normally to hold the door 70 closed but permitting it to be opened. This may conveniently be accomplished by placing in the housing a spring, 10, one end of which is secured to the door and the other end to one of the end walls of the housing; 75 this spring being under an initial tension sufficient to hold the door closed or to close it when left free to do so.

Extending lengthwise through the hood and journaled at its ends in the end walls 80 thereof is a blade holder, 11, which is adapted to engage and hold the back edge of a blade, 12, having a single cutting edge. The parts are so proportioned that when in the position shown in full lines in Fig. 1, the 85 blade extends out through the front of the hood into operative relation with the support and guard, 5; a suitable catch or lock, 13, being provided to hold the swinging door 90 in this position. When the swinging door 95 is opened into the position shown in dotted lines in Fig. 1, the blade is drawn from the supporting shelf and swings downwardly through the open top and rear side of the upper member of the housing. Then when 100 the door is permitted to close the blade assumes the position shown in full lines in 105 110

Figs. 2 and 3 which is the stropping position.

Within the housing is a suitable stropping device adapted to strop the blade when the latter hangs in its stropping position. In the arrangement shown, the stropping device consists of a segment of a cylinder, 14, having its cylindrical surface suitably prepared; the member 14 being carried by a shaft, 15, parallel with the swinging holder, 11, and spaced apart therefrom a distance less than the width of the blade plus the radius of the stropping cylinder. Therefore when the mutilated side of the cylinder is up as illustrated in Fig. 2, the blade may hang freely but, if the stropping element is turned in one direction or the other, one of the radial surfaces, 16 and 17, engages with the side of the blade, swinging the blade laterally until it eventually assumes a position tangent to the cylinder. One of these positions of the blade is indicated in dotted lines in Fig. 2. During the continued rotation of the stropping element it acts in the well known way on the blade to sharpen the same. Then, when the edge of the blade reaches the trailing end or edge of the cylindrical stropping surface, it is no longer restrained but is permitted to swing back to the position illustrated in full lines. If now the stropping element be turned in the opposite direction, the cutting edge will be stropped from the opposite side of the blade, the blade being first swung over to one side of the housing and finally being left free to drop back into its vertical position again. In this way by rocking the stropping element back and forth through an angle of less than 360 degrees, the blade will be stropped alternately from opposite sides. After the stropping is completed, the door is swung back into the position shown in dotted lines in Fig. 1, the blade is raised so as to bring it above the supporting shelf and guard, 5, and the door is then permitted to close, carrying the blade forward into its shaving position in operative relation to the guard.

If desired, there may be placed on the inner side of the door a flat spring, 18, a similar spring, 18, being placed on the front wall of the upper member of the housing; these springs being in position to engage with the sides of the blade when it is swung out of its vertical position and, being placed under tension before the blade reaches a position tangential to the stropper, serving to start the blade from an inclined position to a vertical position whenever the edge comes opposite the mutilated portion of the stropping cylinder.

The stropping cylinder may be actuated by a suitable crank, 19, fixed to one end of the shaft 15. The handle, 20, of the crank is preferably slidably mounted in the radial

arm thereof so that when it is brought opposite a hole, 21, in one of the end walls of the handle, 2, of the housing, it may be pushed inwardly as indicated in dotted lines in Fig. 3, so as no longer to project materially, and at the same time locking the crank against accidental rotation. The parts are preferably so disposed that when the crank is locked in the manner just explained, the mutilated side of the stropping cylinder is directed upwardly in order to permit the razor blade to be swung freely into a stropping position.

If desired, a suitable pawl device, 22, having a projecting pin, 23, to be engaged by the crank, may be provided to coöperate with a toothed wheel, 24, fixed to the shaft, 15, so as to make it necessary to complete a stroke of the crank started in either direction before the crank can move in the opposite direction.

In the arrangement shown in Figs. 4 to 7 inclusive, the housing is made of lower and upper members, 25 and 26, which may take generally the form of the members 1 and 3 except that the upper member is closed at the ends and at the sides and is open only at the bottom and at the top of the contracted neck, 27, in which the upper end of the member 26 terminates. From one of the long side edges, which may be called the front edge of the neck, 27, of the housing extends laterally a suitable support and guard, 28, for the razor blade, 12. The blade is fixed at one edge in a holder, 11, such as heretofore described, this holder lying within and journaled at its ends in the end walls of a hood, 29. The hood rests upon the reduced neck of the housing, being hinged thereto at one end by means of a suitable hinge, 30, and there being a suitable catch, 31, at the opposite end of the hood to lock it down upon the housing. The hood is provided on the front side thereof with a forwardly-projecting part or flange, 32, which presses down upon the top of the blade in the shaving position and yieldingly holds it in place.

Within the housing is a stropping cylinder or roller, 14, such as heretofore described, and there being a pawl and ratchet, 22 and 24, if desired, to compel the user to complete a stropping stroke, once started, before beginning a return stroke. When it is desired to strop the blade, the catch 31 is released, the hood is swung upwardly into the position shown in dotted lines in Fig. 6 and, when the blade lies directly over the open top of the contracted neck of the housing, the hood is again lowered and locked in place.

The stropper may be actuated by a suitable detachable crank, 33, the handle, 34, of which may be adjusted so as to make it aline with the radial arm of the crank. The crank

- may therefore be detached and housed in a compartment requiring only a small cross sectional area. Such a compartment may conveniently be obtained by providing the 5 housing with a hollow handle, 35, closed at the free end by means of a screw cap, 36, or the like; the actuating crank for the strop 65 per from a position in which a blade held therein rests on said guard to a position in which said blade hangs in proximity to said strop.
5. A safety razor comprising a holder, a strop 70 mounted on the holder, said holder having a guard at a point above the strop, a device adapted to grip a razor blade in the vicinity of one of its long edges, and means for pivotally supporting said device so as to permit the blade to swing about 75 said edge as an axis and to move bodily from a position overlying said guard to a position in which it hangs down into the vicinity of the strop.
10. The member 11 for holding and pivotally supporting the blade may take any form or construction adapted for the purpose. In Fig. 8 I have illustrated a device which may conveniently be employed, the same consisting 15 of a shaft divided longitudinally into two halves, 36 and 37, each half having half trunnions at its ends as indicated at 38 and 39 respectively. The member 37 is continued beyond the half trunnions, 39, so as 20 to have at its extreme ends complete trunnions, 40. The two halves of the shaft are adapted to be clamped together by means of collars or bushings, 41, which, when they wholly overlie the solid trunnions, 40, permit 25 the two halves of the shaft to be separated from each other but, when they overlie or surround the divided trunnions in whole or in part, lock the two halves of the shaft together. The trunnions, 40, thus 30 serve as the actual bearing supports for the shaft so that the bearings for the shaft need not be disturbed when attaching a blade to or detaching it from the shaft. The blade is of course held in place by laying it between 35 the two halves of the shaft and, in order to give added security to the connection, the blade is preferably provided with one or more holes, 42, through which a pin or pins, 43, on the shaft member 36 may project; the other shaft member having sockets, 44, opposite the pins. These pins therefore 40 serve to lock the blade in position and also to hold the two halves of the shaft in alignment with each other.
45. While I have illustrated and described with particularity only a single preferred form of my invention, I do not desire to be limited to the exact structural details thus illustrated and described; but intend to 50 cover all forms and arrangements which come within the terms employed in the definitions of my invention constituting the appended claims.
- I claim:
55. 1. A safety razor comprising a holder, a strop 110 mounted in said holder, and a blade pivotally supported above the strop so as to be capable of swinging from a shaving position to a stropping position.
60. 2. A safety razor comprising a holder, a strop 115 mounted in the holder, a guard on the holder above said strop, a pivotal support adapted to engage a razor blade at one edge, and means for adjusting said sup-
3. A safety razor comprising a housing, a strop 120 arranged in the housing, said housing having a guard at the upper end for supporting a blade in shaving position, said housing being open at the top, a blade-carrying element adapted to engage a blade in the vicinity of one of the long edges of the latter, and means for supporting said element so as to permit it to move from a position in which a blade held thereby rests on said guard to a position in which the blade hangs 90 down into the housing so as to bring its cutting edge into operative relation to the strop.
4. A safety razor comprising a housing, a strop 125 arranged in the housing, said housing having a guard at the upper end for supporting a blade in shaving position, said housing being open at the top, a blade-carrying element adapted to engage a blade in the vicinity of one of the long edges of the latter, and means for supporting said element so as to permit it to move from a position in which a blade held thereby rests on said guard to a position in which the blade hangs 95 down into the housing so as to bring its cutting edge into operative relation to the strop.
5. A safety razor comprising a housing open at the top and rear in the vicinity of the top, a guard projecting laterally from the front of the housing near the top, a strop 130 within the lower portion of the housing, a cover for the open portions of the housing hinged at its lower end to the housing, and a blade-carrying element journaled in the upper portion of said cover, the parts being so proportioned that when the cover is opened it permits the blade to be brought either above said guard or be projected into the housing and when the cover is closed holds the blade on the guard or permits it to swing in the housing in operative relation to the strop.
6. A safety razor comprising a holder 135 having a laterally-projecting guard on the front side, a strop mounted on the holder in rear of and below said guard, and means for supporting a razor blade in shaving position on the guard or in a stropping position in which it hangs down behind and free from the guard with its edge in proximity to the strop.
7. A safety razor comprising a housing having a guard at the upper end for supporting a blade in shaving position, a cylindrical strop 140 arranged within the housing with its axis parallel with the plane of said guard, said strop having a section extending throughout the length thereof cut 145 away, and means for supporting a blade either in shaving position on said guard or depending into the housing free from said

guard with its cutting edge in operative relation to the stropper.

8. A safety razor comprising a housing having a guard at the upper end for supporting a blade in shaving position, blade-holding means constructed and arranged to hold said blade on said guard or permit it to hang

freely in the housing, and means in the housing for stropping the blade alternately from opposite sides thereof when the blade occupies the last mentioned position. 10

In testimony whereof, I sign this specification.

JOHN W. McAULIFFE.
